COMBINED VESTEE AND SCARF

Florence Beatrice Crummens, New York, N. Y.

Application June 14, 1954, Serial No. 30,980

Term of patent 7 years

(Cl. D3—25)

To all whom it may concern:

Be it known that I, Florence B. Crummens, a citizen of the United States and a resident of the city, county, and State of New York, have invented a new, original, and ornamental Design for a Combined Vestee and Scarf, of which the following is a specification, reference being had to the accompanying drawings, forming part hereof and in which:

The single figure is a plan view of a combined vestee and scarf showing my new design.

I claim:

The ornamental design for a combined vestee and scarf, substantially as shown.
